UNITED STATES PATENT OFFICE.

JOHN BELL, OF SEATTLE, WASHINGTON.

COMBINED WASHING-MACHINE AND CLOTHES-BOILER.

1,010,570.

Specification of Letters Patent.

Patented Dec. 5, 1911.

Application filed March 30, 1911. Serial No. 617,841.

To all whom it may concern:

Be it known that I, JOHN BELL, a citizen of the United States, residing at Seattle, in the county of King and State of Washington, have invented certain new and useful Improvements in Combined Washing-Machines and Clothes-Boilers, of which the following is a specification.

This invention relates to domestic laundry devices; and its object is to produce a combined wash boiler and washing machine of inexpensive construction which will prove convenient to use and efficient in operation.

With these ends in view, the invention consists in the novel construction and combination of parts, as will be hereinafter described and claimed.

In the accompanying drawings, Figure 1 is a transverse vertical section of an embodiment of my invention; and Fig. 2 is a fragmentary horizontal section taken through 2—2 of Fig. 1.

In carrying out the present invention, I provide a wash boiler 5, which is preferably circular and has a detachable cover 6. Within this boiler is a removable liner 7 formed with corrugations whose flutings are disposed vertically, as illustrated. The lower edge of the liner rests upon the bottom 5' of the boiler while its upper edge is disposed to be at a distance below the top of the boiler. Located interiorly of the liner is a radially corrugated partition 8 which is supported upon peripherally disposed legs 9 so as to afford a space 10 between the rim of the partition and the boiler bottom 5'. One or more of the legs are provided with a toe or toes, such as 9', extending into a groove of the liner to prevent any rotary motion obtaining to the partition. Said partition is of a conical shape and at the apex thereof is provided with an opening 11 which serves as a passage for water from the space below the partition to a chamber 12 thereabove and within a prismatical casing 13 which is rigidly secured to the partition.

The peripheral wall of the casing is fenestrated by punching the same from the outside so as to provide tongues 14 extending in sloping directions downwardly from the upper edge of each of the wall apertures 14', as clearly shown in Fig. 1. The office of these tongues is to direct outwardly water in the ascending travel of the same through the chamber and more particularly from the lower rows of apertures. Supplemental to

these tongues I provide axially of the casing a directrix which is supported from the top wall 13' of said casing. Said directrix is formed of a series of annular spaced shoulders 15 and below each such shoulder is a recess to provide an inverted conoidal configuration in the risers 15', so to speak, between the successive steps, or shoulders, and subjacent to the lowest one. Extending axially through the boiler cover 6 and for a distance therebelow is a tube 16 which serves as a journal bearing for an upright spindle 17. At the upper end of the spindle 17 is a transversely arranged bar 18 which is employed for a handle whereby the operator rotates the spindle. At the lower end of the spindle is secured a plurality of radially disposed arms 19 whose outer ends are directed downwardly and terminate, desirably, in knobs 20.

In operation, the boiler is placed on a stove and supplied with saponified water. The clothes, according to their character, are put into the water either before or after the latter becomes hot. The heat arising from the stove acts through the boiler bottom 5' to raise the temperature of the water thereabove. Upon being heated the body of water ascends from said bottom to be replaced by water flowing inwardly through the space 10 below the partition rim. The ascending water is guided by the partition through the opening 11 into the chamber 12 wherein it continues to rise subject to the diverging effect performed thereupon by the directrix peripheral surfaces 15' so that the water is caused to move outwardly to encounter the tongues 14. These tongues, in turn, cause the water to pass outwardly into the body of water, in which the clothes were deposited, surrounding the casing 13. The water continues to flow from the apertures 14' and by reason of the water returning through the opening at 10 below, there is a circulation established having in its course a central upward travel and a reverse movement at the outside of the casing 13. Where but a small batch of cloth is being washed, the water will percolate through the mass to a greater extent than where a large quantity is being operated on. In the last mentioned state, a portion of the water will pass downwardly through the troughs of the liner.

During or subsequent to the clothes scalding operation as above described, the clothes

are revolved about the casing through the instrumentality of the handle 18 revolving the arms 19 whose depending ends engage the clothes. In thus turning about the casing 13, the clothes rub against the corners of the peripheral faces thereof and likewise against the corrugations of the liner 7 and those of the partition 8 whereby the washing is accomplished.

10 The invention is of extreme simplicity and is peculiarly adapted for family washings where many of the soiled pieces, containing lace for example, are unable to withstand the rough usages common to certain varieties 15 of clothes washers.

What I claim, is—

The combination with a wash boiler, of a corrugated liner for the boiler, a radially corrugated conoidal shaped partition mounted above the bottom of the boiler and pro-

vided with an opening at its highest part, a prismoidal casing secured to the partition and inclosing a chamber which communicates through said opening with the space below the partition, the wall of said casing being provided with separate annular rows of apertures, a tongue projecting inwardly from the top of each of said apertures, and a solid diatrix suspended from the top of said casing and formed of a series 25 of superposed inverted conoidal shaped portions, said diatrix extending in the opening in said partition, a conoidal portion being positioned in the same horizontal plane with each row of openings.

JOHN BELL.
